N. L. MORTENSEN

CONTROLLER FOR DRIVEN MACHINES

Filed July 24. 1922

INVENTOR.

Nicla L. Mortensen.
BY Frankart Stubbael

ATTORNEY .

UNITED STATES PATENT OFFICE.

NIELS L. MORTENSEN, OF MILWAUKEE, WISCONSIN, ASSIGNOR TO THE CUTLER-HAMMER MFG. CO., OF MILWAUKEE, WISCONSIN, A CORPORATION OF WISCONSIN.

CONTROLLER FOR DRIVEN MACHINES.

Application filed July 24, 1922. Serial No. 577,020.

To all whom it may concern:

Be it known that I, NIELS L. MORTENSEN, a citizen of the United States, residing at Milwaukee, in the county of Milwaukee and 5 State of Wisconsin, have invented new and useful Improvements in Controllers for Driven Machines, of which the following is a full, clear, concise, and exact description, reference being had to the accompanying 10 drawing, forming a part of this specification.

This invention relates to improvements in controllers for motor driven machines and is particularly applicable to motor driven rubber mills.

15 Owing to the many instances where rubber mill operators have been injured by having their hands drawn between the mill rolls it has become quite customary to provide safety controllers whereby in emergencies 20 the mill may be quickly stopped. However, in order to extricate the operator's hands it has heretofore been necessary to effect manual separation of the mill rolls and owing to the high temperature of such rolls and the 25 time required to effect separation thereof the injuries received are usually augmented by severe burns. It has also been proposed to provide controllers which are adapted in emergencies to both 30 stop and reverse the mill rolls but in practice it has been found that reversal of the rolls is likely to produce additional injuries.

The present invention has among its objects to provide a controller for rubber mills 35 and other driven machines which is adapted upon emergency operation to effect quick stopping of the driven machine and automatic separation of the rolls thereof.

Another object is to provide a controller 40 of the aforesaid character having power operated means for adjusting the mill rolls said means being normally adapted to operate the rolls at a speed suitable for adjustment purposes and being adapted in emergencies to effect separation of the rolls at 45 an increased speed.

Various other objects and advantages will hereinafter appear.

The accompanying drawing illustrates 50 schematically an embodiment of the invention which will now be described it being understood that the embodiment illustrated is susceptible of modification without departing from the scope of the appended 55 claims.

Referring to the drawing the driven machine is represented schematically by a pair of rolls 1 and 2 the former to be driven by a motor 3 and the latter being adjustable with respect to the former by suitable screw down 60 means represented by a screw 4.

Screw 4 is adapted to be driven through the medium of mechanism of the character disclosed in the patent to Clark T. Henderson, No. 1,157,307 of October 19, 1915, such 65 mechanism comprising in general a power operated driving member 5, a hand operated driving member 6, a common driven member 7 and interposed gearing whereby braking of either driving member provides a drive 70 through a medium of the other.

Member 5 is driven by a motor 8 having an armature A and a field F said armature being fixed to driving member 5 and being normally restrained by a brake 9 having an 75 electromagnetic operating winding 9a. Driving member 6 is aligned with and preferably journaled within the driven member 7 and has keyed thereto a pinion 10 in constant mesh with a pair of epicyclic gears 11 80 loosely journaled on lugs 12 projecting from driven member 7. A loose casing 13 encloses gears 10 and 11 and is provided with bearings 14 and 15 on the driving and driven shafts respectively. Casing 13 is provided 85 with internal gear teeth adapted to mesh with gears 11 and external gear teeth adapted to mesh with a pinion 16 fixed to shaft 5. Driving member 6 is provided with a hand wheel 17 for operating the same and driven member 7 has a bevel pinion 18 adapted to mesh with a bevel gear 19 fixed to screw shaft 4.

As set forth in the aforementioned patent, with motor 8 stationary, adjustment of roll 95 2 can be effected by rotating drive shaft 6 through the medium of hand wheel 17 and upon restraint of shaft 6 motor 8 is adapted to effect such adjustment. However, as hereinafter set forth motor 8 is adapted 100 in emergencies to operate at a relatively high speed to effect separation of the rolls 1 and 2 and during such operation shaft 6 is adapted to be automatically restrained by a solenoid operated brake 20. Brake 20 105 is of a conventional type, the same being provided with opposed brake shoes which are normally released by a spring and are adapted to be set by a solenoid winding 21.

Motor 3 can be started and stopped by 110

any suitable type of controller and if desired the rolls can be quickly stopped in emergencies by suitable braking means. However, for simplicity of illustration a circuit breaker 23 is shown for establishing power connections for motor 3 from lines L' and L², said circuit breaker being provided with a tripping coil 23^a adapted to open the same for stopping of said motor. The control means for motor 8 includes a pair of double pole electromagnetic reversing switches 25 and 26 for establishing reverse power connections for the armature of said motor through a resistance R, and a double pole electromagnetic switch 27 for excluding said resistance from the armature circuit in emergencies.

The controller further includes a master switch M for controlling reversing switches 25 and 26 and brake 9 and emergency control means including an electromagnetic relay 28, an emergency control element 29 and a limit switch 29^c. Master switch M includes stationary contacts a', a², a³ and a⁴ adapted to co-operate with a drum having contacts b', b³ and b⁴ arranged to the left of said stationary contacts and contacts c', c² and c⁴ arranged to the right thereof. Relay 28 is provided with a normally closed contact 28^a and three normally open contacts 28^b, 28^c and 28^d, and as hereinafter set forth the same controls the energizing circuits of switches 26 and 27 and brakes 9 and 20. Emergency control element 29 includes normally open contacts 29^a and 29^b, the former contacts being adapted to control the energizing circuit of relay 28 through the medium of limit switch 30 and the latter the tripping circuit of circuit breaker 23. Limit switch 30 is normally closed and is adapted to open upon upward movement of roll 2 to a given position.

The operation of the aforescribed controller together with the circuit connections therefor will now be more fully set forth. As before stated upon restraint of shaft 6 motor 8 is adapted to act through the aforescribed transmission mechanism to effect adjustment of roll 2 in opposite directions with respect to roll 1. In the controller illustrated the field F of motor 8 is permanently connected across lines L' and L² and it is assumed the reversing switch 25 is adapted to establish power connections through resistance R for operation of motor 8 in a direction for raising of roll 2 with respect to roll 1 while reversing switch 26 is adapted to establish power connections through said resistance for reverse operation of the motor such power connections being obvious from the drawing and requiring no description. Switch 25 is energized by movement of the master switch M into its right hand position and with said master switch in this position the energizing

circuit for switch 25 extends from line L' to contact a' through contacts b' and b³ to contact a³ by conductor 30 through the normally closed contacts 28^a of relay 28 by conductor 31 through the operating winding of said reversing switch and by conductors 32 and 33 to line L². Movement of master switch M into its right hand position also establishes an energizing circuit for the brake 9, extending from line L' to contact a' through contacts b' and b⁴ to contact a⁴ by conductor 34 through the operating winding 9^a of said brake and by conductors 35 and 33 to line L². Upon movement of master switch M into its left hand position the aforescribed energizing circuit for brake 9 is established through contacts c' and c⁴ while reversing switch 26 is energized by a circuit extending from line L' through contacts a', c', c² and a² by conductor 36 through the operating winding of said reversing switch and by conductor 33 to line L².

Assuming now that it is desired to stop the driven machine and effect separation of the rolls thereof, emergency switch 29 is depressed. Upon depression of switch 29 switch 28 opens to stop motor 3, the tripping coil 23^a being then connected across lines L' and L² by contact 29^b through circuit connections which are apparent from the drawing. Contact 29^a simultaneously energizes relay 28 through a circuit extending from line L' through contact 29^a by conductor 38 through limit switch 29' by conductor 39 through the winding of relay 28 and by conductor 40 to line L². In responding relay 28 insures interruption of the energizing circuit of reversing switch 25 by opening of its contact 28^a and the contact 28^b thereof establishes an energizing circuit for reversing switch 26 extending from line L' by conductors 41 and 42 through contact 28^b by conductors 43 and 36 through the operating winding of reversing switch 26 and by conductor 33 to line L². As before stated, closure of reversing switch 26 establishes power connections for effecting operation of motor 8 in a direction to move roll 2 upwardly and immediately upon establishment of such power connections brake 9 is energized by a circuit extending from line L' by conductors 41 and 42 through contact 28^c by conductors 44 and 34 through winding 9^a and by conductors 35 and 33 to line L², while brake 20 is energized by a circuit extending from line L' by conductor 41 through contact 28^d by conductor 45 through solenoid winding 21 and by conductor 46 to line L². Also immediately upon closure of relay 28, switch 27 is closed to exclude resistance R from the armature circuit of motor A, said switch being energized by a circuit extending from line L' by conduction

tor 41 through contact 28^a by conductor 47 through the operating winding of switch 27 and by conductors 48 and 33 to line L². Thus it is apparent that in emergencies 5 motor 8 will operate at an increased speed to effect upward movement of roll 2, the driving connection therefor being maintained by restraint of driving member 6 through the medium of brake 20. When 10 roll 2 is moved into a given upper limit the same effects opening of limit switch 29' and the aforescribed energizing circuit of relay 28 is interrupted and upon opening of said relay switches 26 and 27 15 return to normal position and brake 20 is released while brake 9 is reset.

What I claim as new and desire to secure by Letters Patent is:

1. In a controller for driven machines 20 having relatively adjustable work-performing parts adapted to act upon material fed therebetween in combination means for effecting relative adjustment of said parts and control means associated with said former means and operable in emergencies to effect a given relative adjustment of said parts.

2. In a controller for driven machines 30 having relatively adjustable work-performing parts adapted to act upon material fed therebetween in combination means for starting and stopping said machine and for effecting relative adjustment of said parts and control means operable in emergencies 35 to stop said machine and to simultaneously effect separation of said work-performing parts.

3. In a controller for driven machines 40 having relatively adjustable work-performing parts adapted to act upon material fed therebetween in combination driving means for said machine, means for effecting relative adjustment of said parts and control means including an emergency control element operable to stop said machine and to 45 simultaneously effect quick separation of said work-performing parts.

4. In a controller for driven machines 50 having relatively adjustable work-performing parts adapted to act upon material fed therebetween in combination means operable in emergencies to effect a given relative adjustment of said work-performing parts, said means including means whereby said 55 work-performing parts may be adjusted at will.

5. In a controller for driven machines 60 having relatively adjustable work performing parts adapted to act upon the material fed therebetween in combination power operated means normally adapted to effect relative adjustment of said work-performing parts at a given speed and means operable in emergencies to effect a given relative adjustment of said parts at an increase speed.

6. In a controller for driven machines 70 having relatively adjustable work-performing parts adapted to act upon material fed therebetween in combination driving means for said machine, power operated means controllable at will to effect relative adjustment of said parts and emergency control means operable to stop said machine and to effect a given operation of said power operated means.

7. In a controller for driven machines 75 having relatively adjustable work-performing parts adapted to act upon material fed therebetween in combination a driving motor for said machine power operated means 80 for effecting relative adjustment of said work-performing parts and control means for said driving motor and said power operated adjusting means operable to effect quick stopping of said machine and to simultaneously effect quick separation of said work-performing parts.

8. In a controller for driven machines 85 having relatively adjustable work-performing parts adapted to act upon material fed therebetween in combination a driving motor for said machine a reversible motor for varying the spacing of said work-performing parts and control means for said motors operable in emergencies to stop said former 90 motor and to insure operation of the latter in a direction to effect separation of said work-performing parts.

9. In a controller for driven machines 100 having relatively adjustable rolls adapted to act upon material fed therebetween in combination a driving motor for said rolls, a reversible motor for varying the relative spacing of said rolls and control means for said motors including an emergency control 105 element operable to effect stopping of said former motor and simultaneous operation of the latter motor in a direction to effect separation of said rolls.

10. In a controller for driven machines 110 having rolls adapted to act upon the material fed therebetween and screw down means for varying the relative spacing of said rolls, in combination means for starting and stopping said driven machine, a reversible 115 motor for varying the spacing between said rolls, power transmitting mechanism between said motor and said screw down means including a part requiring restraint to render said motor effective, and to be released to render the same ineffective and emergency control means for said machine 120 including means for stopping said machine and for simultaneously braking said part and effecting operation of said motor in a direction to effect separation of said rolls.

In witness whereof I have hereunto subscribed my name,

NIELS L. MORTENSEN.
